UNITED STATES PATENT OFFICE.

GANO S. DUNN, OF EAST ORANGE, NEW JERSEY, ASSIGNOR TO CROCKER-WHEELER COMPANY, OF AMPERE, NEW JERSEY, A CORPORATION OF NEW JERSEY.

DYNAMO-ELECTRIC MACHINE.

SPECIFICATION forming part of Letters Patent No. 792,762, dated June 20, 1905.

Application filed October 24, 1904. Serial No. 229,738.

To all whom it may concern:

Be it known that I, GANO SILICK DUNN, a citizen of the United States of America, and a resident of East Orange, county of Essex, 5 State of New Jersey, have invented certain new and useful Improvements in Dynamo-Electric Machines, of which the following is a specification.

This invention relates to an improvement in 10 dynamo-electric machines of the substantially inclosed type, wherein the bearing for the end of the armature-shaft adjoining the commutator is supported by an end shield which is secured to the inclosing frame, preferably by 15 screws, this being a type of construction of manifest advantage by reason of the convenience of manufacture and machining of the parts to secure proper alinement.

The object of my invention is, while retaining 20 this type of construction, to do away with the complications, large number of parts, difficulty of insulation, danger of vibration, and liability to shrinkage and consequent looseness usually found in brush-riggings and to 25 provide an inexpensive brush-rigging wherein in the end shield is utilized directly as a support for the brush-holders, the attaching-screws of which form the connection for the outside conductors, and thereby save a special 30 terminal board. Suitable provision is made for the proper setting of the brushes at their proper points for minimum sparking by the mere provision of elongated or large holes or 35 slots for the screws which hold the end shield to the frame, so that such shifting of the brushes as may be required is effected by loosening the screws which hold the end shield to the frame and rotating the shield as a whole.

40 In the accompanying sheet of drawings, which forms a part of this application, Figure 1 is a vertical section through the inclosing frame of a dynamo-electric machine embodying my invention, the front shield being 45 broken away on the line A B of Fig. 2 and the rear shield being broken away on the line A C. Fig. 2 is an elevation of the machine in which portions of the front shield and the inclosing frame at the right are broken away.

The invention herein disclosed is embodied 50 in a direct-current machine, which I have developed in various sizes, ranging from one-fourth to three horse power, and which are chiefly used as electric motors.

A cast-steel frame 1, which also serves as a 55 magnet-frame, is conveniently of substantially cylindrical form with open ends and two inwardly-projecting cores 2 cast thereon. Form-wound field-coils 3, substantially rectangular in shape, surround each of the cores, 60 and an armature 4 lies between the coils, all of these parts being inclosed and protected by the frame. The open ends of the frame are bored out in alinement with the axis *xx* 65 of the machine and faced off at right angles thereto. A front end shield 5 and a rear end shield 6 cover the open ends. Flanges 7, which are parts of the end shields, are turned 70 to fit the bored holes in the ends of the inclosing frame and are means for centering and alining the shields with respect to the frame. The shield 5 incloses and protects the commutator 8 and supports a bearing 9 for the armature-shaft adjoining and outside the commutator. Four insulating-bushings 10, of porcelain, pass through tapering 75 holes in the shield and are fastened in place by type-metal 11. Metallic studs 12 pass through two of these bushings and screw into brush-holders 13 on the inner side of the shield. Nuts 80 14 on the outer ends of the studs draw the brush-holders firmly against the ends of the bushings. Tongues 15, formed on the hubs of the brush-holders, fit into slots in the ends of the bushings and hold the brush-holders firmly 85 in angular relations, so that the brush-holders and studs are rigidly supported by the end shield, and the outwardly-projecting ends of the studs can be employed as the terminals of the machine, to which the conductors leading 90 away from the machine are connected. The other two bushings carry terminal studs 16 for the field connections. Nuts 14' on the ends of the studs clamp them in the bushings. Additional nuts 14'' bind the ends of the field-wires on the inner side of the shield and the field connections on the outer side of the shield. Carbon brushes 17 are guided in the

- brush-holders and pressed by springs 18 against the commutator in properly-spaced relation, which in the bipolar machine illustrated is at diametrically opposite points of the commutator. As the proper diametrical position of the brushes for the least sparking is different according to the direction of rotation and whether the machine is run as a dynamo or as a motor or if the machine is to be run in both directions, as the proper position is intermediate of the positions for running in either direction exclusively, provision is necessary for the adjustment of the brushes around the commutator. For this purpose 5 circumferential slots 19 are placed in the rim of the shield, and cap-screws 20 pass through these slots and are tapped into the frame of the machine to permit of circumferential adjustment of the end shield to bring the brushes 10 to the desired positions. These slotted holes are unequally spaced around the rim, so that assembly is possible only in one way, and the user will be prevented from attempting to assemble differently to adapt the motor to different suspensions.
- To render the machine adaptable to wall or ceiling suspension, as well as to support from the floor, in all of which positions the bearing, which is self-oiling, must be kept with 15 the same side up, provision is made for the setting of the bearing to either of four positions without removing or loosening the end shield and disturbing the adjustment of the brushes. The support for the bearing in the 20 end shield is chambered on all sides of the shaft for an oil-well. There are four holes 21 around the sides of this chambered hub of the end shield, and a petcock 22 is screwed in whichever one is lowest, depending on the 25 suspension to draw out the oil. The other holes are closed with three plugs 23. The bearing is transversely slotted on its upper side, so that a ring 24 can rest in the slot and on the shaft, dip in the oil, and serve as a 30 means for raising oil from the well and onto the shaft. The bearing must be so set in the 35

support that the slot in which the ring lies will be on the upper side. It is held in place by a set-screw 25, and holes are drilled into the bearing for the point of the set-screw at four places, so that the bearing can be set with the slot uppermost in either of the four positions in which it may be required to place or suspend the machine.

No provision is made for shifting the bearing in the rear end shield with respect to the shield. Instead the shield is detached from the frame and turned to bring the bearing right side up when the direction of suspension of the machine is changed. The shield 55 is held to the frame by four screws 26, which are evenly spaced, so as to permit of the attachment of the shield to the frame in either of the four positions necessary for this purpose.

What I claim as new, and desire to secure by Letters Patent of the United States, is—

In a dynamo-electric machine, the combination with the field, armature and commutator, of an inclosing frame for the field and armature, brush-holders, a bearing for the armature-shaft adjoining and outside the commutator, and an end shield provided with a support for said bearing and circumferential slots, means for centering the end shield with 70 respect to the inclosing frame, screws passing through the slots for attachment of the shield to the inclosing frame, insulating bushings rigidly supported in the end shield, metallic studs rigidly supported in the bushings 75 and passing through the shield, the inner ends of the studs serving as supports for the brush-holders and the outer ends serving as terminals for the machine, substantially as described.

Signed by me at East Orange, New Jersey, the 21st day of October, 1904.

GANO S. DUNN.
